UNITED STATES PATENT OFFICE.

WILLIAM B. BIGELOW, OF NEW YORK, N. Y., ASSIGNOR TO WM. KNABE & CO. MANUFACTURING COMPANY, OF BALTIMORE, MARYLAND.

DESIGN FOR A GRAND-PIANO LEG.

SPECIFICATION forming part of Design No. 21,248, dated December 22, 1891.

Application filed November 17, 1891. Serial No. 412,211. Term of patent 7 years.

To all whom it may concern:

Be it known that I, WILLIAM B. BIGELOW, a citizen of the United States, residing at New York, in the county of New York and State of New York, have invented a certain new and original Design for Grand-Piano Legs; and I do hereby declare the following to be a full, clear, and exact description of the invention, such as will enable others skilled in the art to which it appertains to make and use the same.

My invention relates to an original design for grand-piano legs.

The leading features of my design are an upper portion with a representation of a panel on its outer face having "braided" work thereon, a central portion in the form of a globe, having a series of circular panels thereon and carved decorations in the spaces adjacent to said panels, and a lower portion of a generally-oblong form having representations of vertical grooves thereon.

The accompanying drawing represents my design.

A represents the upper portion of a grand-piano leg, B the central portion, and C the lower portion. The outer face of the portion A is made to represent a panel *a*, having a border *b*, said border being continued at its center into the panel *a* and made to repre-

sent braided work *c*. The ends of the portion A are carved to represent two scrolls *d* *d'*, one within the other.

Immediately beneath the portion A the leg is carved to represent a recessed or grooved portion *e*, and beneath the portion *e* is a spherical body *f*. The spherical portion or globe *f* has represented thereon a series of circular panels *g* *g'*. A border *h* is represented above and below the spherical portion *f*, which border is continued to form a border for the circular panels *g* *g'*. Beneath the spherical portion *f* is represented a carved ring *i*. At the top of the lower portion C is represented a ring *j* of small balls, and beneath this ring *j* a series of vertical grooves *k* is represented.

Having fully described my design, what I claim as new and original, and desire to secure by Letters Patent, is—

The design for piano-legs herein shown and described.

In testimony whereof I have signed this specification in the presence of two subscribing witnesses.

WM. B. BIGELOW.
